(57) **CLAIM**

The ornamental design for an air chuck, as shown and described.

DESCRIPTION

FIG. 1 is a right-side elevational view of an air chuck showing my new design, wherein a trigger is in a depressed position, and wherein a left-side elevational view is a mirror image of the right-side elevational view;
FIG. 2 is a front elevational view of the air chuck shown in FIG. 1;

FIG. 3 is a rear elevational view of the air chuck shown in FIG. 1;

FIG. 4 is a top plan view of the air chuck shown in FIG. 1;
FIG. 5 is a bottom plan view of the air chuck shown in FIG. 1;

FIG. 6 is a perspective view depicting the front, top and side views of the air chuck shown in FIG. 1;

FIG. 7 is a perspective view depicting the rear, top and side views of the air chuck shown in FIG. 1;

FIG. 8 is a perspective view depicting the bottom, front and side views of the air chuck shown in FIG. 1;

FIG. 9 is a perspective view depicting the bottom, rear and side views of the air chuck shown in FIG. 1;

FIG. 10 is a right-side elevational view of an air chuck showing my new design, wherein a trigger is in a released position, and wherein a left-side elevational view is a mirror image of the right-side elevational view;

FIG. 11 is a front elevational view of the air chuck shown in FIG. 10;

FIG. 12 is a rear elevational view of the air chuck shown in FIG. 10;

FIG. 13 is a top plan view of the air chuck shown in FIG. 10;
FIG. 14 is a bottom plan view of the air chuck shown in FIG. 10;

FIG. 15 is a perspective view depicting the front, top and side views of the air chuck shown in FIG. 10;

FIG. 16 is a perspective view depicting the rear, top and side views of the air chuck shown in FIG. 10;

FIG. 17 is a perspective view depicting the bottom, front and side views of the air chuck shown in FIG. 10; and,

FIG. 18 is a perspective view depicting the bottom, rear and side views of the air chuck shown in FIG. 10.
